Primary Examiner — Michael C Stout*Assistant Examiner* — Fitzgerald L Butac(74) *Attorney, Agent, or Firm* — Fish & Richardson P.C.**(57) CLAIM**

The ornamental design for a perforating gun contact device, as shown and described.

DESCRIPTION

FIG. 1 is a top, right perspective view of a perforating gun contact device, according to the new design;

FIG. 2 is a top, left perspective view thereof;

FIG. 3 is a right-side view thereof;

FIG. 4 is a left view thereof;

FIG. 5 is a front view thereof;

FIG. 6 is a rear view thereof;

FIG. 7 is a top view thereof; and,

FIG. 8 is a bottom view thereof.

The broken lines show portions of a perforating gun contact device which form no part of the claimed design.
